UNITED STATES PATENT OFFICE.

JOHN SADLER, OF ROCKFORD, IOWA.

ADJUSTABLE TONGUE HOUND.

Application filed January 29, 1923. Serial No. 615,465.

To all whom it may concern:

Be it known that I, JOHN SADLER, a citizen of the United States, residing at Rockford, in the county of Floyd and State of Iowa, have invented certain new and useful Improvements in Adjustable Tongue Hounds, of which the following is a specification.

In carrying out the present invention it is my purpose to provide an adjustable tongue hound which may be readily and quickly applied to vehicles and adjusted to fit between the wagon hounds, and wherein the tongue hounds may be adjusted singularly with respect to each other so as to fit properly between the wagon hounds.

It is also my purpose to provide adjustable tongue hounds whereby the tongue may be securely connected to the wagon hounds in such manner as to prevent slipping of the tongue and wherein the tongue may be readily swung up and down whenever necessary or desired.

Furthermore, I aim to provide a construction of adjustable tongue hounds wherein the hounds may be readily and quickly adjusted with respect to each other and which will embody comparatively few parts, and these so arranged and correlated as to reduce the possibility of derangement to a minimum.

With the above recited objects in view, and others of a similar nature, the invention resides in the construction, combination and arrangement of parts set forth in and falling within the scope of the appended claims.

In the accompanying drawings:

Figure 1 is a top plan view of my improved adjustable tongue hound.

Figure 2 is a sectional view on the line 2—2 of Figure 1.

Figure 3 is a similar view on the line 3—3 of Figure 1.

Figure 4 is a like view taken on line 4—4 of Figure 1.

Referring now to the drawings in detail, 1—1 designate the wagon hounds which may be constructed in any suitable manner and which converge toward each other from the rear ends toward the front.

My improved adjustable tongue hound construction is placed within the wagon hounds 1—1 and comprises side bars 2—2 arranged alongside of the inner surfaces of 55 the wagon hounds 1—1, respectively. In

the present instance, each side bar 2 comprises a body 3 of wood and a metal strip 4 riveted, as at 5, or otherwise secured to the outer edge of the body 3 and designed to lie adjacent to the inner side of the wagon hound 1. Formed in each side bar 2 is a series of transverse openings 4' adapted to interchangeably align with an opening 5' formed in the adjacent wagon hound 1. Through these alinings openings is passed a pivot rod 6 having its outer ends threaded and equipped with nuts 7. The pivot rod 6 has a direct connection between the tongue hounds and the wagon hounds and at the same time permits of a vertical swinging movement of the wagon hounds, in order that the tongue may be raised and lowered.

Arranged between the bars 2—2 of the tongue hound construction is the inner end of the wagon tongue 8. Adjacent to its inner extremity the tongue 8 is formed with a series of transverse openings 8' to receive the bar 6, so that a pivotal connection may be established between the tongue and the hounds 1 and a connection established between the tongue and the tongue hounds construction.

Bolted or otherwise secured to the opposite sides of the tongue 8 in advance of the wagon hounds are metal straps 9 having their rear ends formed to provide vertical pivot pin openings 10. Arranged transversely of the tongue 8 above and below the same are pairs of straps 11—11. The inner ends of the straps of each pair 11 overlap each other, and the overlapping ends of the straps of each pair are formed with interchangeably alining openings 12. When any two of the openings 12 are brought into alinement with each other, 95 said alining openings also align with an opening formed on the tongue, and through these alining openings is passed a bolt 13. Thus, a connection is established between the pairs of straps 11—11 and the tongue, 100 as clearly shown in Figure 4 of the drawing. The outer ends of the straps 11—11 overlie and underlie, respectively, the bars 2 adjacent to the forward ends thereof, and these outer ends are connected to the bars 2 by means of pivot bolts 14 that pass through the outer ends of the straps 11 and the bars 2. The bolts 14 also pass through the inner ends of links 15—15 arranged above and below the bars 2, as clearly shown 110

in Figure 2 of the drawings. The forward ends of the links 15 are arranged above and below the pivot openings 10 in the straps 9 and are connected to such pivot openings 5 by pivot bolts 16.

- Arranged transversely of the tongue 10 at the inner extremity thereof above and below such tongue are pairs of straps 17—17, respectively, as clearly shown in Figure 3 of the drawings. The straps of each pair 17 have their inner ends overlapping each other and formed with interchangeably alining openings 18. When any two of the openings 18 are in alinement, they also aline with an opening in the tongue, and through these alining openings is passed a pin 19, as clearly shown in Figure 3 of the drawings. Thus, a connection is established between the pairs of straps 17 and the tongue. 10 The outer ends of the straps 17 overlie and underlie, respectively, the bars 2 adjacent to the inner ends of such bars and are adapted to connect to the bars 2 by means of pivot bolts 20 that pass through the straps 17 15 and are interchangeably associated with a series of openings 21 formed in each bar 2.

From the foregoing description, taken in connection with the accompanying drawings, it will be seen that by means of the 20 pairs of straps 11 and 17 the bars 2 of the tongue hounds construction may be adjusted toward and away from each other and may also be adjusted to correspond to the angle of the wagon hounds 1—1, while 25 by means of the links 15 and the pivot rod 6 a connection is established between the tongue, the tongue hounds and the wagon hounds which hold the tongue against slipping.

I have entered into a detailed description of the construction and relative arrangement of parts embraced in the present and preferred embodiment of my invention in order to impart a full, clear and exact 40 understanding of the said embodiment. I do not desire, however, to be understood as confining myself to the specific construction and relative arrangement of parts, inasmuch as in the future practice of the in-

vention various changes and modifications 50 may be made such as fall within the scope of my invention as defined by my appended claims.

Having thus described the invention, what is claimed as new, is:—

1. In adjustable tongue hounds construction, the combination with the wagon hounds, of side bars arranged against the inner sides of said wagon hounds, respectively, a wagon tongue having its inner end 60 arranged between said bars, a pivot rod extending through said wagon hounds, side bars and tongue, said side bars being each formed with a series of openings through which said pivot rod may be interchangeably 65 passed, whereby the longitudinal positions of said bars with respect to the wagon hound may be varied, adjustable connections between the forward ends of said side bars and tongue and adjustable connections 70 between the rear ends of said bars and tongue, whereby the angular positions of said bars with respect to each other may be changed to correspond to the angular positions of the wagon hounds. 75

2. In adjustable tongue hounds construction, the combination with the wagon hounds, of side bars arranged against the inner sides of said wagon hounds, respectively, a wagon tongue having its inner end 80 arranged between said bars, a pivot rod extending through said wagon hounds, side bars and tongue, said side bars being each formed with a series of openings through which said pivot rod may be interchangeably 85 passed, whereby the longitudinal positions of said bars with respect to the wagon hound may be varied, adjustable connections between the forward ends of said side bars and tongue and adjustable connections 90 between the rear ends of said bars and tongue, whereby the angular positions of said bars with respect to each other may be changed to correspond to the angular positions of the wagon hounds, and links connecting said 95 tongue to the forward ends of said bars.

In testimony whereof I affix my signature.
JOHN SADLER.
